UNITED STATES PATENT OFFICE.

JACOB WILLIAM SPENSLEY, OF MANCHESTER, ENGLAND.

ROTARY DISINTEGRATING, PULVERIZING, OR MIXING APPARATUS.

1,215,424.

Specification of Letters Patent.

Patented Feb. 13, 1917.

Application filed December 23, 1915. Serial No. 68,372.

To all whom it may concern:

Be it known that I, JACOB WILLIAM SPENSLEY, a subject of the King of Great Britain, and resident of 29 Barton Arcade, Deansgate, Manchester, in the county of Lancaster, England, chemical engineer, have invented certain new and useful Improvements Relating to Rotary Disintegrating, Pulverizing, or Mixing Apparatus, of which

10 the following is a specification.

This invention relates to rotary disintegrating, pulverizing or mixing apparatus of the type wherein disks are used with intercalating pins thereon, and the material is 15 disintegrated or mixed by being caused to pass across the space between two such disks and between the rows of pins thereon, while either one disk rotates and the other is stationary, or the disks rotate in opposite directions.

The present invention has for its object to provide an improved construction wherein the pins can be readily secured in position in the disks and can be removed therefrom 25 in a convenient manner, for replacement when required. Another object of the invention is to secure absolute rigidity in the mounting of the pins and absolutely correct 30 positioning thereof. To this end the pins are forced into holes formed in the disks which are provided with suitable liners or bushings adapted to coact with flats formed on the rear faces of the disks around the 35 ends of the holes to effect rigid mounting and positioning of the pins. A further object of the invention is to permit of the use of plain pins of a hard quality of steel, harder than can be screw-threaded or riveted, which pins can be secured in position so 40 as not to leave any projecting heads on the back of the disks when revolving in the machine.

The construction according to the invention is shown in the accompanying drawings, wherein:—

Figure 1 is a half section of a pair of the disks with pins thereon, and

Fig. 2 is a partial plan view to a smaller scale, with the pins and grooves on the top plate shown in dotted lines.

Fig. 3 shows a detail.

Plain pins *a* are used with plain shallow cylindrical heads *b* of somewhat larger diameter. Such pins can be formed from rods of the required quality of steel by cutting on an automatic machine, whereby great ac-

curacy and uniformity can be secured. The disks *c* and *d* have holes for pins of graduated sizes formed in concentric circles therein. These holes are plain bored holes 30 according to this invention, and at the rear of the disks flats are turned as shown in Fig. 1, around each ring of holes so that the heads *b* of the pins will be flush against the same when driven in; this is necessary 35 as the disks are dished but the pins are parallel to the turning axis. The holes are made of such a size that the pins *a* are a force-fit or driving-fit therein. The heads *b* of the pins are then inclosed by cover plates 70 *e* and *f* which are dished to lie against the backs of the disks *c* and *d*; these cover plates have grooves turned therein as at *g*, to accommodate the heads *b* of the pins. The cover plates may be secured in any suitable way, as for instance by the use of set screws *h*; these are shown as having projecting heads, except for the inner set in the bottom plate. If desired however, they may all engage in countersunk recesses in 80 the backs of the plates. The grooves at *g* are only just deep enough to accommodate the pin-heads *b* so that they prevent the pins from being forced out backwardly in use.

When it is required to replace any or all of the pins *a*, the cover plate *e* or *f* is easily taken off by removing the set screws *h*, and the pins can then be knocked out, after which new ones are driven in to replace 90 them and the cover plate is replaced. The cover plate need not be of any great thickness or weight, and for instance a plate of three-eighths of an inch to half an inch in thickness will be quite strong enough when 95 pins with heads one-eighth of an inch thick are used. The cover plate will usually be made of the same size as the disk on which it fits, and may be secured in other ways than that above mentioned.

If pins *a* are used which are approximately as hard as the metal of the disks *c* and *d*, the pins and the sides of the holes in the disks will both be compressed slightly during the driving in of the pins, and new 105 pins when driven in subsequently to replace the worn ones will also hold sufficiently tightly in the holes. If very hard pins are used, it may be necessary to fit sleeves or bushes of relatively soft metal in the holes, 110 so that they can be replaced each time when the pins are renewed. Such bushes can be

used in all cases if preferred. Fig. 3 shows pins *a* engaging in bushes *i* in the plate *d*.

The holes in the disks and the parts of the pins which engage therein may be slightly 5 tapered in order to provide a wedging fit; the cover plates will then prevent the pins from being forced out during use. The taper would be so slight that it could not be shown clearly in the drawing.

10 The disks are shown as being grooved at *j* in concentric circles facing the ends of the pins *a* of the opposing disk members, slight clearances being left in order to avoid any packing of material which might injure the pins. The method of mounting the pins referred to above, secures the most accurate 15 positioning of the pins combined with rigidity, and the clamping of the pin heads in grooves is an important feature in securing 20 this result.

Having thus described my invention what I claim as new and desire to secure by Letters Patent is:—

1. In a rotary disintegrating, pulverizing 25 or mixing apparatus, the combination with a pair of dished disks each having a plurality of concentric grooves in their adjacent faces, the grooves of one disk alternating with the grooves in the other disk, and each 30 disk having a plurality of holes formed in concentric circles and alternating with the grooves, the axes of the grooves and holes being parallel to the central axes of the disks, fixed bushes 35 for lining said holes, and flats formed on the rear faces of the disks around the ends of the holes, a plurality of hardened plain pins having en-

larged heads forced into said holes and arranged so that the pins in one disk face the concentric grooves in the other disks 40 with a slight clearance between the ends of the pins and the grooves, cover plates for the rear faces of said disks provided with a plurality of concentric grooves of sufficient depth just to receive the pin heads and 45 prevent axial movement of the pins, and means for securing the cover plates to the disks.

2. In a rotary disintegrating, pulverizing or mixing apparatus, the combination with 50 a pair of disks each having a plurality of concentric grooves in their adjacent faces, the grooves of one disk alternating with the grooves in the other disk, and each disk having a plurality of holes formed in concentric 55 circles and alternating with the grooves, the axes of the grooves and holes being parallel to the central axes of the disks, fixed bushes for lining said holes, a plurality of hardened plain pins having enlarged heads forced 60 into said bushes and arranged so that the pins in one disk face the concentric grooves in the other disk with a slight clearance between the ends of the pins and the grooves, cover plates for the rear faces of said disks 65 provided with a plurality of concentric grooves of sufficient depth just to receive the pin heads and prevent axial movement of the pins, and means for securing the cover plates to the disks.

JACOB WILLIAM SPENSLEY.
